UNITED STATES PATENT OFFICE

JAMES COOPER, OF SYRACUSE, NEW YORK, ASSIGNOR TO HALL & MCCHESNEY, OF SYRACUSE, NEW YORK, A CORPORATION OF NEW YORK

METHOD OF EMBOSSED LEATHER AS APPLIED TO BACKS OF LOOSE LEAF BINDERS

Application filed September 26, 1932. Serial No. 634,924.

This invention relates to a method of embossing leather as applied more particularly to the backs of loose-leaf binders of the class set forth in my pending application Serial No. 617,739, filed June 17th, 1932.

These binders are extensively used for binding considerable numbers of relatively large record sheets into book form as permanent records to be used more or less frequently in the transaction of business and in view of the fact that the backs are subjected to the most severe strains and wear, it becomes necessary to construct them in a strong and substantial manner and also to protect the titles and other indicia thereon against obliteration.

For this purpose, the back of each book preferably comprises a core of relatively stiff and hard rawhide or other suitable material of concavo-convex cross section extending the entire length of the book and having its lower convex face provided with longitudinally spaced transverse bosses or cushions of cork or equivalent more or less elastic material adhesively or otherwise secured thereto.

A layer of relatively tough but pliable leather is then adhesively or otherwise secured to the outer convex surfaces of the core and bosses so as to follow closely the contours thereof and thereby to add its resiliency to that of the cushions and at the same time to produce the desired finish to the back and to enable the title and other indicia to be printed or impressed thereon.

In order that the finishing layer of leather may be closely applied to all portions of the convex surfaces of the back and to the cushioned bosses thereon, it is desirable to use a single piece of leather of sufficient size to cover said surfaces and to extend over and around the marginal edges of the core and also to emboss the leather to conform to the contour of the bosses before its application to the core.

It is found that wet or moistened leather may be embossed in greater relief and with greater accuracy of detail than dry leather and that when embossed in a more or less wet condition and then allowed to dry it re-

tains its embossed configuration indefinitely without materially affecting its original marginal dimensions.

Heretofore, it has been customary to moisten the entire strip of leather which is 55 to form the covering for the back and then to adhesively apply this moistened strip by hand pressure or by the use of hand tools into all of the intaglio parts and also against the relief parts of the strip, all of which 60 are excessively laborious and requires the services of highly skilled employees.

The main object of the present invention is to limit the moistening of the leather to relatively narrow areas at the junctions of 65 the relief with the intaglio parts and then to subject these moistened areas to pressure between suitable dies so as to preserve the original surface finish and color of all other parts and at the same time to preform those 70 parts complementary to the form of the surface to which the embossed leather is to be applied and thereby to assure a better quality of work and increased output with less skillful labor.

Another object is to render the operation of assembling the embossed leather back piece upon the previously cushioned surface of the core less laborious and more expeditious and reliable than has heretofore been practised.

In other words, I have sought to permanently preform the leather back piece complementary to the bosses on the lower face of the core of the back so that it will instantly and accurately seat itself upon and around said bosses so that it may be adhesively applied to the core with greater ease and efficiency than would be possible under the 90 previous methods.

Other objects and uses will be brought out in the following description.

In the drawing:

Figure 1 is a perspective view of a flat 95 strip of leather of sufficient size to form a covering for the back of a loose leaf binder.

Figure 2 is a perspective view of the same strip of leather embossed to conform to 100

the contour of the bosses on the core of the back unit of the binder.

Figure 3 is an enlarged sectional view of a set of moulds for embossing the leather strip as shown in Figure 2.

Figure 4 is a transverse sectional view of the moulds taken on line 4—4, Figure 3.

Figure 5 is a perspective view of the leather strip shown in Figure 2, except that its marginal edges are shaped to fold over and upon the marginal edges of the core of the back unit.

Figure 6 is a perspective view of the detached core to which the embossed leather strip shown in Figure 5 is to be applied.

Figure 7 is a perspective view of the back unit including the core with the leather strip applied thereto.

Figure 8 is an enlarged longitudinal vertical sectional view of one end of the back unit taken on line 8—8, Figure 7.

Figure 9 is a transverse sectional view taken on line 9—9, Figure 7.

In order that the invention may be clearly understood, I have shown in Figures 6, 8 and 9, a core 1 of rawhide or equivalent comparatively stiff and hard material of concavo-convex cross section and of sufficient length to extend from end to end of a loose leaf binder, such for example, as that shown in my pending application referred to, said core being enclosed in a casing 2 of fabric adhesively secured to its opposite faces to form a unitary part thereof, said core and its casing constituting the supporting base for the back unit of the loose leaf binder.

Upon the convex side of this supporting base is adhesively secured a plurality of bosses 3, 4 and 5 which are arranged in longitudinally spaced relation and extend transversely from edge to edge of the base or core 1.

These bosses 3, 4 and 5 are preferably made of cork or equivalent more or less resilient material to form cushions adapted to relieve the shock upon other parts of the binder and to reduce the noise incidental to the use of the book when placed edgewise vertically with its back resting upon a table or other support.

As illustrated, the bosses 3 and 4 are provided with relatively narrow intaglio parts 6 and 7 in longitudinally spaced relation to form intervening and somewhat wider relief parts 8 while the intermediate boss 5 is provided with narrow intaglio parts 9 and 10, also in longitudinally spaced relation to form narrow relief ribs 11 and a relatively wider sunken panel 12.

The outer surfaces of the core 1 between and at opposite ends of the bosses 3, 4 and 5 and also the outer surfaces of the bosses are arcuate in cross section and are arranged so that the outer faces of the relief parts 8 and

11 will be of about the same radius having a

common center or axis to take thrust of the book when resting upon its back.

The outer surfaces of the core and its bosses 3, 4 and 5 may therefore be said to be embossed in that they are provided with the intaglio and relief parts referred to, and the purpose of the present invention is to preform a leather strip, as 13, Figure 1, with intaglio and relief parts complementary to those of the core 1 so that it may be easily and quickly applied to said core by any suitable adhesive substance to form a facing or covering therefor in such manner that it will conform closely to the intaglio parts of the core.

In carrying out this purpose, the leather strip 13 will be made of sufficient size to cover the entire convex surface of the core 1 and bosses 3, 4 and 5 and to overlap around and upon the inner surfaces of the marginal edges of the core in the manner shown in my pending application referred to.

The portions of this leather strip 13 which are to be applied to the relatively narrow intaglio parts 6, 7, 9 and 10 of the bosses 3, 4 and 5 are first moistened by any suitable means to render them sufficiently pliable for embossing into said intaglio parts without moistening any of the remaining parts of the strip.

The means for embossing the moistened parts of the leather strip 13 preferably comprises a pair of opposed pressing elements 14 and 15 having their meeting faces provided with separate sets of cooperative dies 6', 7', 9' and 10' arranged in substantially the same longitudinally spaced relation as and complementary to the intaglio parts 6, 7, 9 and 10 respectively of the bosses 3, 4 and 5.

After the relatively narrow zones of the leather strip 13 have been moistened in the manner described, the strip is placed between the pressing elements with its moistened zones in registration with their corresponding sets of dies so that when the pressing elements are brought into pressing coaction the moistened portions of the strip will be embossed by the dies 6', 7', 9' and 10', to form corresponding intaglio parts 6'', 7'', 9'' and 10''.

It will be noted upon reference to Figure 3 that the portions of the meeting faces of the dies 14 and 15 between the dies are cut away to form recesses 8', 12' and 1', corresponding respectively to the relief portions 8, sunken panel 12 and to the spaces between the bosses 3, 4 and 5 of the core 1 to prevent pressure of the pressing elements upon the unmoistened parts of the leather and thereby to preserve the original finished condition of the leather of the unmoistened, unpressed parts.

If desired, the pressing elements 14 and

15 may be heated to effect the drying and setting of the shape of the previously moistened parts of the leather while under pressure between the dies and for this purpose both pressing elements are provided with heating chambers 14' and 15' for receiving a heating agent such as steam from any available source of supply, not shown, or the moistened parts of the leather may 10 be cold-pressed by the same dies.

In either process the embossed leather strip will be removed from between the pressing elements as soon as the pressing operation is completed to be subsequently 15 applied to the convex surfaces of the core 1 and bosses 3, 4 and 5.

In order that the embossed strip may be conveniently and closely fitted around and upon the marginal edges of the core 1 without 20 excessive folds in the manner shown in my pending application referred to the edges of its opposite ends are provided with suitable cutouts 20 and 20', as shown in Figure 5.

25 When the leather strip is embossed and treated in the manner described, its embossed parts will be complementary to the like contours of the outer surface of the core 1 and its bosses 3, 4 and 5 so as to 30 closely conform to said contours when the strip is loosely seated thereon preparatory to fastening the same thereto.

In order to secure the embossed strip of leather in place, the surfaces to which it is 35 to be secured, or the inner surface of the strip, will be coated with a suitable adhesive material after which the strip will be placed in proper position upon said surfaces with corresponding complementary parts in 40 registration and then pressed in place by hand to assure the adhesion of all parts thereof to said surfaces, thereby simplifying the operation and greatly increasing the output and at the same time assuring a better and more permanent job than has heretofore 45 been commonly practised ready to be assembled with the other parts of the loose leaf binder.

The moisture may be applied by a brush 50 or otherwise, to previously marked zones as 13' shown by dotted lines in Figure 1 or through the openings of a previously prepared stencil not shown, but arranged to correspond to said zones so that the remaining 55 portions of the leather may remain unmoistened and thereby retain their original finished luster.

It is to be understood, however, that other contours or configurations may be embossed 60 in leather under the same or analogous

process and for other purposes without departing from the spirit of the invention.

What I claim is:

1. In book binding in which the back of the book is provided with a relatively stiff 70 core having longitudinally spaced bosses, the herein described method of applying a leather facing to the embossed surface of said core consisting in selecting a strip of leather of sufficient area to cover said surface, embossing a portion of the strip complementary to said surface before applying it thereto and then adhesively applying the embossed strip to said surface with complementary parts in registration. 75

2. The herein described method of applying a single piece of leather to an embossed surface consisting in moistening the leather, embossing the same under pressure complementary to said embossed surface, and then adhesively securing the embossed leather to the embossed surface with the complementary parts in registration. 80

3. The herein described method of making leather facings for the embossed back of a 90 book binding, consisting in moistening parts of the leather which are to cover the intaglio parts of said embossed back, embossing said moistened parts complementary to the intaglio parts of the back, and adhesively 95 securing the embossed leather to the embossed back with complementary parts of both elements in registration. 95

4. A leather facing for the embossed back 100 of a book binding in which the leather is embossed complementary to the embossed back before its application thereto.

5. The herein described method of applying a leather facing to the back of loose leaf binders in which the back is provided with raised bosses, said method consisting in moistening only those parts of the leather which are to cover the edges of the bosses, compressing said leather between suitable dies to make said moistened portions conform to the shape of said edges, and then adhesively securing the embossed leather to said back with its embossed portions in registration with the edges of the bosses. 110

6. The herein described method of applying a leather facing to a surface having relief and intaglio parts consisting in moistening only the zones of the leather which are to cover the junctions of said parts, subjecting the moistened zones to pressure between dies complementary to the contour of said junctions, and adhesively securing the leather to said surface with pressed zones in registration with corresponding junctions. 115 120
